LOUDSPEAKER DISPLAY FIXTURE

William R. Saidel, Olympia Fields, Ill., assignor to Electronic Industries Incorporated, South Holland, Ill.

Filed Sept. 20, 1971, Ser. No. 182,292

Term of patent 14 years

Int. Cl. D6—04

U.S. Cl. D6—20

FIG. 1 is a front perspective view showing my new design for a loudspeaker display fixture, the unshown back being plain and unornamented;

FIG. 2 is a side elevational view of my new design, the opposite side being a mirror image of the illustrated side; and

FIG. 3 is a plane view showing my new design.

I claim:

The ornamental design for a loudspeaker display fixture, substantially as shown and described.
